UNITED STATES PATENT OFFICE.

ALBERT HARVEY GLEASON, OF WABASH, INDIANA.

WAGON-TONGUE SUPPORT.

SPECIFICATION forming part of Letters Patent No. 291,532, dated January 1, 1884.

Application filed September 27, 1883. (No model.)

To all whom it may concern:

Be it known that I, ALBERT HARVEY GLEASON, a citizen of the United States, residing at Wabash, in the county of Wabash and State of Indiana, have invented a new and useful Improvement in Wagon-Tongue Supports, of which the following is a specification.

In that class of wagons and carriages having tongues or thills it is desirable to have the same supported so that its weight shall not be wholly carried by the team. At the same time it is not desirable that the tongue should be rigidly held at any fixed height while in use, as this would produce a pounding action on the necks of the team. It is also desirable that when the vehicle is not in use its tongue shall not stick out in the way, as it would do if then held at the same height that it was held while in use. The object of my invention is to overcome these objections.

To this end my invention consists in the construction and combination of parts hereinafter described and claimed, reference being had to the accompanying drawings; in which—
25 Figure 1 is a side elevation, part in section, of a portion of a wagon-tongue, one of the hounds, the axle, and my supporting device. Fig. 2 is a plan view of the same, showing both hounds; and Fig. 3 is a detail view of the supporting device, partly in transverse vertical section.

A represents the tongue, pivoted at *a* to the hounds B, which are framed, as usual, to the wood-work of the axle C.

35 On the rear end of the tongue A, I secure a spring, D, coiled like a flat clock-spring. On the outer end of this spring I secure a hook, E, and at a little distance from the end I secure another hook, F. These hooks are of a peculiar form. Each hook is practically double, having one body extending across the breadth of the spring and secured to its back, and a hook projecting forward at each edge of the spring. These hooks are adapted to 40 engage two studs, *a'*, of an open block, G, the body of which is secured to the axle C, the sides projecting forward from the body, and the two studs *a'* projecting inward toward each other from the sides. The vertical space

between the sides of the block to the rear of 50 the studs is enough to allow the double hooks to play freely therein. The distance between the ends of the studs is sufficient for the width of spring D to pass between them; yet the studs are close enough together to engage both 55 hooks at the sides of the spring. The lower nose of each hook faces forward, so that when the spring descends each hook will be wedged to the rear by contact with the studs, and the upward nose of each hook is so slanted as to 60 guard the hook in its upward movement and cause it to be wedged forward by the studs, so that quick sweeping movements of the tongue through its arc of motion, either up or down, do not engage the hooks with the studs, thus 65 avoiding serious shocks on the spring and hooks in case the tongue were to fall from a high angle of elevation.

To engage the hooks and studs it is necessary to raise the tongue slowly until the desired hook springs forward below the studs; then let the tongue down, and the hooks will engage the studs and support the tongue elastically, as desired. The lower hook will be set in such relation to the tongue as to support it 70 at the desired height for use, and the upper hook will be fixed to the spring at such a height as to support the tongue at the desired angle of elevation when not in use. I prefer to fasten the spring D at some distance 75 from its end to the rear end of the tongue, in order that the end to the rear of the fastening may be turned up to re-enforce the body of the spring.

What I claim as my invention, and wish to 80 secure by Letters Patent, is—

1. In a wagon-tongue pivoted to swing vertically between the hounds, a spring secured upon the rear end of the tongue, and two hooks secured to said spring at different heights, in 85 combination with a block secured to the axle, having one or more studs adapted to engage said hooks, as shown and described.

2. The combination, with a flat coiled spring having two pairs of hooks projecting from its 90 sides, as described, secured to a wagon-tongue, of a block secured to the axle, having two forward projections farther apart than the width

of a pair of hooks, carrying two inwardly-projecting studs far enough apart to permit said spring to pass between them, and adapted to engage the hooks at the sides of the spring, as shown and described.

3. The combination, with a block having the forward-projecting sides and inwardly-projecting studs described, secured to a wagon-axle, of a spring secured to the tongue, and

two pairs of hooks secured to the spring, adapted to engage said studs, each pair of hooks being provided with noses adapted to guide the hooks past the studs, as described.

ALBERT HARVEY GLEASON.
